UNITED STATES PATENT OFFICE

2,009,800

ADJUSTABLE REACTANCE TRANSFORMER

Allan B. Hendricks, Jr., Pittsfield, Mass., assignor
to General Electric Company, a corporation of
New York

Application November 1, 1934, Serial No. 750,933

3 Claims. (Cl. 171—119)

My invention relates to adjustable reactance transformers of the type having a movable winding. It is often desirable that some arrangement be provided for adjusting the reactance of a transformer to control the secondary current, as for example where the transformer supplies current for welding operation. The general object of the invention is to provide an improved-adjustable reactance transformer with convenient and compact means for moving one of its windings and holding it in any desired position.

The invention will be better understood from the following description taken in connection with the accompanying drawings in which Fig. 1 is a longitudinal sectional view of a transformer constructed in accordance with the invention, this figure being taken on line 1—1 of Fig. 5; Figs. 2 and 3 are enlarged perspective views of a support for the movable winding of the transformer; Fig. 4 is an end view of the transformer with the operating handle removed; and Fig. 5 is a sectional view on the line 5—5 of Fig. 1.

Like reference characters indicate similar parts in the different figures of the drawings.

The transformer shown in the drawings includes a magnetic core 10 having a winding leg 11. The core 10 is formed of four rectangular sections 12. The winding leg 11 includes one side of each of the core sections 12 fitted together to leave a central longitudinal space 13, the other sides of the core sections 12 providing return paths for the magnetic core flux. The four core sections 12 are secured together by end clamps 14 and 15 and rods or bolts 16. The winding leg 11 is surrounded by windings 17 and 18, the windings being separated from the winding leg by an insulating cylinder 19. The winding 17 is secured in position at one end of the winding leg 11 but the winding 18 is free to move along the winding leg and thus to change its position with respect to the winding 17.

A threaded rod or screw 20, which extends into the space 13 in the winding leg of the core, is supported at its outer end by a ball-bearing 21 so that this screw 20 is free to rotate but cannot move longitudinally. The inner end of the screw 20 is threaded into an internally threaded nut 22 which fits loosely in the space 13. The space 13 is square in cross section and the nut 22 is also square so that the nut, while free to move lengthwise of the space, cannot turn in it. Four wings or brackets 23 secured to the nut 22 extend outwardly through slots 24 in the inner sides of the core sections 12. These core sections 12 are formed of thin, magnetic laminations and the

slots 24 are formed by inserting non-magnetic spacing strips 25 at suitable places in the core sections. The insulating cylinder 19 is also provided with slots 26 in alignment with the slots 24 of the core sections 12. The outer ends of the brackets 23 extend through these slots 26 in the insulating cylinder and are secured to a ring 27 which supports the movable winding 18. The nut 22 is formed with shoulders 29 which engage opposite edges of the inner ends of the brackets 23 and the brackets are secured to the nut between these shoulders by small projections 29 integral with the nut and headed over in openings 30 in the inner ends of the brackets.

The screw 20 may be rotated by a handle 31 secured to its outer end. The nut 22, brackets 23 and ring 27 form a support for the movable winding 18 and this support with the movable winding may be easily moved toward or away from the fixed winding 17 by rotating the screw 20 in any proper direction, thus adjusting the reactance of the transformer as desired. As the movable winding 18 is moved away from the fixed winding 17 the reactance of the transformer is of course increased and as it is moved toward the fixed winding 17 the reactance is decreased. It is obvious that the transformer may be used in any desirable position and that it is immaterial which winding is the primary winding and which is the secondary winding.

The invention has been explained by describing and illustrating a particular form thereof but it will be obvious that changes may be made without departing from the spirit of the invention and the scope of the appended claims.

What I claim as new and desire to secure by Letters Patent of the United States, is,—

1. A transformer including a magnetic core having a winding leg with a longitudinal space therein, two windings surrounding the winding leg, one of said windings being movable along the winding leg, a support for the movable winding, and means within said space and engaging said support for adjusting the position of the movable winding along the winding leg.

2. A transformer including a magnetic core having a winding leg with a longitudinal space therein, two windings surrounding the winding leg, one of said windings being movable along the winding leg, said winding leg having slots between said space and the movable winding, a support extending through said slots and secured to the movable winding, and means within said space and engaging said support for adjusting

the position of the movable winding along the winding leg.

3. A transformer including a magnetic core having a winding leg with a longitudinal space therein, two windings surrounding the winding leg, one of said windings being movable along the winding leg, said winding leg having slots

between said space and the movable winding, a threaded member in said space, brackets extending through said slots and secured to said member and to the movable winding, and a screw engaging said member for adjusting the position of the movable winding along the winding leg.

ALLAN B. HENDRICKS, JR.
